PACKING FOR VAPOR-LIQUID CONTACT
APPARATUS

Leslie B. Bragg, Ridgewood, N.J., assignor to Packed Column Corporation, New York, N.Y., a corporation of New York
Filed Dec. 1, 1958, Ser. No. 777,483
1 Claim. (Cl. 261—106)

This invention relates to contact devices effecting contact between liquid and vapor or gas in fractionating columns, absorbers, scrubbers and the like, and more particularly pertains to an improvement of the type of packing material described in the patent of R. C. Scofield, No. 2,470,652 dated May 17, 1949, wherein each tray is composed of a mat formed from a plurality of layers of foraminous material, said mat having spaced parallel ridges and valleys to form intermediate sloping areas along which the liquid flows and being fabricated to conform to the horizontal section of the column in which the mat is installed.

The present invention provides a packing material that is made of small unit pieces which in the size for a four inch high tray can be introduced into a column shell through an opening as small as ten inch in diameter.

The packing trays are made of single sheets or layers.

As a result of imperfections of manufacture and uncontrollable temperature stresses commercial column shells are never truly round in cross-section and are seldom even of the exactly correct perimeter. Consequently, the rigid construction of a unitary prefabricated tray does not permit a satisfactory fit between the inner column wall and the packing.

As a practical expedient it was necessary to construct such trays somewhat smaller in diameter than the inside of the column shell and then to fill the resulting annular space between the tray and the column shell with a packing material such as stainless steel wool or rock wool. This resulted in a non-uniform structure inside the column which permitted channeling of some liquid and possibly also vapor past the trays.

A feature of the present invention is the provision of a packing material which can readily be extended or contracted along the length of the serrations to allow for variations in diameter or out-of-roundness of the column shell and also provision for field trimming of the packing sections when necessary during installation to further insure a close fit at all points between the packing sections and the column wall.

Another object of this invention is the provision of an increased active cross-sectional area for the flow of the vapor or gas and thereby to provide for a greater allowable overall vapor or gas velocity.

The invention will be better understood from the following description taken in connection with the accompanying drawings forming a part thereof, in which:

FIG. 1 is a schematic vertical sectional view of part of a fractionating column having packing material arranged in accordance with the invention;

FIG. 2 is a horizontal section taken on the line 2—2 of FIG. 1;

FIG. 3 is a detail view partly in side elevation and partly in section showing the construction of a unit from which the tray is formed;

FIG. 4 is a sectional view taken along line 4—4 of FIG. 3.

FIGS. 5, 6 and 7 are sections taken on the lines 5—5, 6—6 and 7—7 respectively of FIG. 3; and

FIG. 8 is a transverse section through a unit illustrating a further embodiment of the invention.

2

Referring to the drawings more in detail:

The packing material of this invention is composed of a grouping of elongated V-shaped units 10 which are arranged to be fitted together to form a tray 11 extending across the entire internal cross-section of the column 12. Successive trays 11 are assembled in stacked relationship to provide a packed column such as is generally shown in FIG. 1.

The elongated V-shaped units 10, the details of which are shown in FIGURES 3-7, each consists of a small channel member 15 located at the point of the V, and formed with a bottom wall 16 and substantially vertical side walls 17. The sloping walls of the V-shaped units are formed by individual panels 18 of foraminous material, such as expanded metal, having openings of a size incapable of supporting a film of the liquid being processed, herein referred to as non-filming or non-capillary foraminous material. Each panel 18 is provided at its upper edge with a flange 19 which is welded or otherwise secured to the outer surface of a vertical wall 17 of the channel member 15. Along its lower edge each of the panels 18 is provided with a vertical flange 20 which is adapted to rest within the channel 15 of the tray below.

The flanges 19 and 20 may comprise unexpanded metal or, if the entire panel 18 is formed from a sheet of expanded metal, the areas of the flanges 19 and 20 may be pressed to a flat state.

As shown in FIGS. 1 and 3-7 the lowermost member 11 is formed by a plurality of units 10 which are placed side by side with their lowermost flanges 20 substantially in contact and with the adjacent flanges 20 of successive units 10 disposed in supporting channels 21. A series of such channels 21 are mounted on supporting members 22 forming a portion of a grid 23 which is secured in the lowermost portion of the column 12. In the embodiment shown four such units 10 are disposed across the column and a portion of a fifth such unit is cut to fill in the space at one side of the column so that the completed tray extends entirely across the cross-sectional area of the column.

Similar trays 11 are stacked on the lowermost tray with the flanges 20 of the units 10 of each tray resting in the channels 15 of the tray below.

In order to permit each unit 10 to be adjusted to a length conforming exactly to the contour of the column, each such unit is formed in two sections, 10a and 10b, which are overlapped as shown in FIGS. 3 and 4. A portion of the channel 15 and of the flanges 19 and 20 of the section 10b is cut back so as to permit the section 10b to nest closely on the surface of the section 10a, thereby forming in effect projecting flanges 18b on the section 10b which rest upon the outer surfaces of the panels 18a of the section 10a.

When the two sections 10a and 10b of the unit 10 are installed in the tower they are adjusted in length and the ends are trimmed if necessary to conform to the contour of the tower at that zone.

The embodiment shown in FIG. 8 is similar to that above described except that the unit 10c of FIG. 8 is of unitary construction and is made from a blank composed of a central portion 15c of unexpanded metal, areas 18c of expanded metal, and side portions 20c of unexpanded metal. The side portions 20c are bent downwardly to constitute the supporting flanges and the central portion 15c is bent inwardly into a U-shaped section similar to the channels 15 above described. In this embodiment the expanded panels 18c are of somewhat greater area than the panels 18. The previous section begins at the rim of the channel 15c and extends to the lower flange area 20c.

In operation, the liquid flows downwardly along the

sloping panels 18 of the packing units and collects in dynamic pools in the lower portions of the V between adjacent panels. The vapor or gas flows upwardly through the openings in the panels, bubbling through the liquid in the pools above mentioned as it rises. The nature of the flow and the shape of the packing promote repeated division and recombinations of both liquid and vapor-gas streams, thereby promoting uniform distribution of both streams.

It should be understood that the invention while describing primarily packing material made of expanded metal type of foraminous section is not limited to the type usually called expanded metal, but also includes other forms of non-capillary foraminous material.

It should also be understood that the packing material may be used in the inverted position with the channels opening downwardly.

The expression "vapor" as used herein and in the claim includes "gas" within its scope.

Inasmuch as changes may be made in the form of the packing disclosed and the material of which the packing is made without departing from the principles of the invention, it will be understood that the invention is not to be limited except by the scope of the appended claim.

What is claimed is:

A column packing for a vapor-liquid contact column, comprising stacked trays, each tray having a plurality of integral units of inverted V-shape cross-section disposed in parallel relationship, each unit having a central channel member having a horizontal bottom wall and vertical side walls extending upwardly therefrom and disposed at the apex of said V-shaped section and panels of non-filming self-supporting foraminous material extending downwardly in an inclined direction on opposite sides of said channel member, said panels having vertical bottom flanges adapted to seat in and be supported by corresponding channel members of corresponding units of the adjacent lower tray, said channel members having a width to hold and maintain the vertical bottom flanges of the units of

5

the adjacent higher tray with said flanges substantially in contact, said flanges substantially filling the channels of said channel members and resting upon and being supported by said bottom walls whereby the stacked trays form a rigid self-supporting structure which may be assembled or disassembled by inserting said bottom flanges in or withdrawing said bottom flanges from their respective supporting channel members, the adjacent panels of contiguous units forming a V-shaped trough for the reception of liquid which flows downwardly along such panels.
